RUSSELL S. DWIGHT, OF CINCINNATI, OHIO

MACHINE AND PROCESS FOR STRETCHING WEBS

Application filed October 29, 1928. Serial No. 315,731.

My invention relates to machines and processes for stretching webs, such as cotton batting and knitted and woven textile material and the like.

There are many instances in the arts generally wherein great expense is incurred in setting up machines for forming webbing of different widths. Often many different sizes of machines are necessary, so that the manufacturer can satisfy the requirements of his purchasers.

It is the object of my invention to provide a process which will enable a manufacturer to make many less standard widths of webbing than have heretofore been required, and to quickly and easily vary the width of a pre-formed web by stretching the web as it is delivered from a machine, thereby allowing him to fill orders for special and unusual widths.

It is further an object of my invention to provide a machine which will automatically stretch webbing at a desired stage in the manufacture thereof. It is my object to provide a machine which will be readily adjustable for making, by a stretching process, desired widths of webbing from webbing of lesser widths than those desired.

The above and other objects to which reference will be made in the ensuing disclosure I accomplish by that certain process and combination and arrangement of parts in a machine of which I have shown a preferred modification.

Referring to the drawings:

Figure 1 is a plan view of my preferred type of web stretching machine.

Figure 2 is a side elevation of the machine shown in Figure 1.

Figure 3 is a diagrammatic view of a web showing the manner in which I distort the fabric of the web to extend it to a desired width.

Figure 4 is a sectional view taken along the lines 4-4 in Figure 3.

The machine diagrammatically illustrated has a supporting frame 1 on which is mounted an axially fixed rotatable shaft 2 and a parallel axially adjustable rotatable shaft 3. Each shaft has in spaced position thereon a

series of discs 4 which may be secured on the shaft with hubs 5. The shaft 3 is mounted in bearings 6 in pivoted arms 7, one on each side of the machine frame. The arms 7 are pivotally mounted as indicated at 8, and a segment casting 9, which has a bearing end 10, may be used to bear against the arms 7, thereby swinging the arms and carrying the axial position of the shaft 3 to a desired position with relation to the shaft 2.

The web of material W to be stretched is passed between the shafts 2 and 3 substantially parallel therewith. Each disc distorts the web in the manner which I have indicated in Figure 3. The material is thus stretched as desired. By increasing the distance between the axes of the shafts, the discs will be carried into a less staggered or overlapping arrangement and the stretching will be less. Inversely, when the axes of the shafts are brought closer together, the depths of the grooves into which the material is distorted becomes greater, and the web is stretched an increased amount.

The segment with which the axial position of the upper shaft is determined may be provided with a series of apertures 11 into which pins may be extended to thus fix the position of the segment. An arm 12 is secured to an eccentric shaft 13 which, when the arm is shifted, bears against the pivoted arms 7.

While the particular construction which I have suggested is one practical way of adjusting the position of the shaft 3, other mechanical devices for adjustably mounting the shaft 3 will immediately suggest themselves for mounting the shaft 3. All that is essential is that the shafts 2 and 3 shall be relatively adjustable so that the discs may be moved into more or less overlapping staggered arrangement.

The shafts 2 and 3 have respectively sprockets 14, 15 mounted on them, which may be driven by chains such as are indicated at 16, 17. The driving sprocket 18, which may be rotated from some suitable source of power, may be used for driving the chains. Since the distance of the center of the driving sprocket from the center of the shaft 3 does

not vary, no adjustments need to be made to the chain.

The edges of the webbing in some material, such as textile fabrics, may be held by a tentering machine, such as is illustrated in the Palmer Patents No. 148,082 and No. 161,896, or with other fabrics such as cotton batting, the edges of the bat may be directed through sets of rollers. In some instances the edges of the web need not be held at all, so that I have not illustrated any particular edge controlling devices as the particular device used, after all, forms no part of my invention, and I do not wish to be limited to any specific device.

I have found that the more disc-like and the more acute the edges of the discs are, the more each disc will serve to stretch and hold the web in stretched position, thereby avoiding the necessity of controlling the edges of the web.

The greatest accuracy may be obtained in stretching webbing laterally in the manner which I have described. For example, if I use twelve inch discs and mount the shafts carrying the discs $12\frac{1}{2}$ inches apart, the web will pass between the discs without being stretched at all. If I then adjust the position of the shafts so that they are only ten inches apart for each set of discs on the shafts the material will be stretched three inches per set.

Referring, for purposes of example, to the diagram in Figure 3. Let us assume that the web to be stretched is eighteen inches wide. If the shafts have five sets of discs on them, the discs being staggered on three inch centers, the web will be stretched from eighteen to thirty inches and the stretching will occur evenly across the whole width of fabric.

If, for example, the distance apart of the edges marked *a*, *a* in Figure 3 is eighteen inches, then the portions marked *b*, *b* will be six inches, the portions marked *c*, *c* will be six inches, and the altitude of the triangles *b*, *c*, *b*, or *c*, *b*, *c* will correspond to the four inches which the shafts 2, 3, have been moved together.

My process is particularly effective in avoiding undue stretching on some parts of the web, as I distort the material in evenly distributed bands. It will be obvious that such a stretching process will be preferable to any system of stretching which consists in pulling apart the outer borders of the webbing.

Having thus described my invention, what I claim as new and desire to secure by Letters Patent, is:—

A web stretching machine comprising a fixed shaft having spaced annular members and an adjustable shaft having annular members spaced to overlap in staggered relation the annular members of said fixed shaft, means for mounting said adjustable shaft in

an arc movable to increase and decrease the staggered relation of said annular members, and a flexible drive for said adjustable shaft having a driving element the axis of which is mounted at the center of the arc of movement of said adjustable shaft.
